VERTICAL ANTENNA

Walter Berndt, Berlin, Germany, assignor to
Telefunken Gesellschaft für Drahtlose Tele-
graphie m. b. H., Berlin, Germany, a corpora-
tion of Germany

Application July 24, 1937, Serial No. 155,447
In Germany August 1, 1936

6 Claims. (Cl. 250—33)

This invention is concerned with a broadcast-
ing transmitting aerial designed to reduce the
short range fading. With this end in view, it
is known to employ vertical antennas whose elec-
trical length is over one-half wavelength ($\frac{1}{2}\lambda$).
The dimensions of the electrical constants of
these antennas are such that a current node
will be produced a small distance above ground.
It is upon the proper position or location of this
5 current node that the extent to which short-
range fading is diminished will depend. The
fixing of the current node according to prior
practice has mostly been effected by choosing
suitable lengths for the aerials, say, by inserted
10 coils and roof capacities. However, this will
establish suitable conditions only for a definite
wave. Thus, if the wave is but slightly altered,
the location of the node will be wrong or faulty,
and the whole chance of reducing the fading will
15 become dubious.

Hence, there is a demand for ways and means
adapted to shift the height of the node steadily,
if possible, after the antenna has been erected.
In the case of self-oscillating iron girders, it is
20 known in the prior art to use an extensible needle
mounted upon the top of the mast. However,
it has been ascertained in practice that the
height above ground of the node will be but little
25 altered by an extension of the needle. Where
antennas with roof or top capacities are em-
ployed, a change in the diameter of the top ring
is capable of insuring sufficient shift in the cur-
rent node. But such a change cannot be brought
30 about during actual operation for the reason that
the demounting of the old ring and the mounting
of the new ring requires a good deal of time.
In the case of antennas comprising built-in coils,
it would finally be feasible to obtain shifts in the
35 location of the current node by a variation in
the number of turns in the coils. However, where
large transmitter powers are involved, the tap-
ping of encased or canned coils causes consider-
able difficulty, not to mention the fact that cor-
40 rect adjustment of the height of the node is
possible only with great difficulty.

In contrast with this prior art, the present
invention is concerned with an arrangement
adapted to secure a steady change in the height
of the current node. According to the invention,
50 the radiating part of the antenna is furnished
with means for altering the cross-section, and
the point where such change in the cross-section
is brought about may be shifted so as to vary
its height above the ground.

55 Actual tests have shown that in the case of an

antenna comprising two parts or members of dis-
similar cross-section, the distribution of the cur-
rent is a function of the point or place where
a change of cross-section is effected. If this
place is located below the current loop, there
5 results a comparatively great height in the loca-
tion of the node (Fig. 1); but if the place where
a change in the cross-section is effected lies at
the current loop, i. e., at a voltage node (Fig. 2),
then the position of the current node will be 10
lower; while if the point of change of cross-
section is located above the current loop (Fig. 3),
this implies and results in the lowest position of
the node. The greater the difference in cross
section and thus of the characteristic impedance 15
of the two halves of the antenna, the more will
the node be displaced upon a shift of the point
of cross-section.

The arrangement of the present invention of-
fers the advantage that the same is not de- 20
pendent upon the provision of top or roof ca-
pacities and built-in coils, and that a change in
the location of the node is accomplishable within
a short time without the use of special acces-
sories. The arrangement is useful also where 25
very large sending powers are involved, while
an incidental merit of the present scheme is that
it conduces to a decrease in the potential pre-
vailing at the base end.

In the drawing:

Figs. 1, 2 and 3 are given merely for the pur-
pose of exposition.

Figs. 4, 5 and 6 illustrate different embodiments
of the present invention.

A few simple exemplified embodiments of the 35
basic idea of the invention are illustrated in
Figs. 4, 5 and 6. The antenna is suspended in-
side wooden tower T. The upper end consists of
a single antenna cable or strand 1. For the bot-
tom part two, three or more antenna cables 2, 40
with the same current or larger cross-sectional
area, are used. For an expeditious shift of the
current node, a third system 3 is provided which
consists of two or more parallel wires (indicated
by dashed lines in the drawing), and these, above 45
and below, are conductively connected with the
fixed antenna conductors 1 and 2, if desired.
The said third system may be raised or lowered,
with a resultant shift in the point where a change
in the cross-section is occasioned.

A particularly great range of variation is ob-
tained in Fig. 5, wherein the lower end or base
of the antenna is in the form of an iron mast or
girder M, and wherein the third system which
conveniently consists of a great number of 50
55

parallel wires 3 is so disposed that it is capable of being lowered into the interior of the mast or girder or else surrounds the mast. Also in this case, the said third system may be conductively associated with the iron girder and the antenna cable or strand 1.

Another exemplified embodiment of the invention is shown in Fig. 6, where the bottom or base end of the antenna tower consists of iron 10 and serves as the lower antenna part. Erected upon this iron tower is a wooden framework T in which the upper part of the antenna 1 is suspended.

The arrangement of this invention is not predicated upon the provision of built-in coils and of roof or top capacities. But these means may be arranged as known in the art and as shown in Figs. 4-6. The general and broad idea underlying the invention is that a shiftable means to 20 change the point of variation of cross-section is provided with a view to reducing short range fading effects, it being, fundamentally speaking, immaterial whether the upper part of the antenna has a smaller cross-section than the lower 25 one, or vice versa. However, for electrical reasons it is recommendable to choose a form of antenna as shown in the drawing, that is, in which the cross-sectional area of the upper part is less than below.

30 What is claimed is:

1. Vertical antenna having an electrical length greater than one half the length of the operating wave and designed for reduced short-range fading, the radiant part of said antenna having a 35 change of cross-section at one part of its length, and means for shifting the part where the change in cross-section takes place in its height above the ground.

2. Vertical sending antenna as claimed in claim 40 1, with the characteristic feature that the upper end consists of a single antenna conductor, the lower part of two or more conductors, and that a third parallel conductor arrangement is connected conductively with the others and so disposed so as to be shiftable in height.

3. Vertical sending antenna as claimed in claim 1, with the characteristic feature that the top end consists of a single antenna conductor, and that the lower end of an iron girder mast, and that a parallel conductor arrangement capable of being lowered in the bottom end is provided.

4. A vertical antenna having an electrical length greater than one-half the length of the communication wave, whereby a voltage nodal point exists in the length of said antenna, said antenna comprising two vertical sections of different cross-sectional areas arranged effectively end to end, and means for effectively shifting the point in said antenna where a change of cross-section occurs, said means comprising an electrical conductor connected simultaneously to both of said vertical sections and vertically adjustable in position over both said sections.

5. A vertical transmitting antenna having an electrical length greater than one-half the length 20 of the communication wave, said antenna comprising two vertical sections of different cross-sectional areas arranged effectively end to end, the upper section constituting a single wire, and means for effectively shifting the point in said 25 antenna where a change of cross-section occurs, said means comprising an electrical conductor connected simultaneously to both of said vertical sections and vertically adjustable in position over both said sections.

6. A vertical transmitting antenna having an electrical length greater than one-half the length of the communication wave, said antenna comprising two vertical sections of different cross-sectional areas arranged effectively end to end, 35 the upper section constituting a single wire, the lower section consisting of a metallic mast, and means for effectively shifting the point in said antenna where a change of cross-section occurs, said means comprising an electrical conductor 40 connected simultaneously to both of said vertical sections, and vertically adjustable in position over both said sections.
